US00D989800S

(12) **United States Design Patent** (10) Patent No.: **US D989,800 S**
Bendale et al. (45) Date of Patent: ** Jun. 20, 2023

(54) **DISPLAY SCREEN OR PORTION THEREOF
WITH GRAPHICAL USER INTERFACE**

- (71) Applicant: **Samsung Electronics Co., Ltd.**, Gyeonggi-do (KR)
- (72) Inventors: **Abhijit Z. Bendale**, Campbell, CA (US); **Pranav K. Mistry**, Saratoga, CA (US); **Bola Yoo**, Seoul (KR); **Kijeong Kwon**, Seoul (KR); **Anil Unnikrishnan**, Los Gatos, CA (US)
- (73) Assignee: **SAMSUNG ELECTRONICS CO., LTD.**, Gyeonggi-Do (KR)
- (**) Term: **15 Years**
- (21) Appl. No.: **29/850,771**
- (22) Filed: **Aug. 23, 2022**

CLAIM

The ornamental design for a display screen or portion thereof with graphical user interface, as shown and described.

DESCRIPTION

The FIGURE is a front view of a display screen or portion thereof with graphical user interface, showing our new design.

The broken lines showing portions of the graphical user interface form no part of the claimed design.
